UNITED STATES PATENT OFFICE

135,387

DESIGN FOR A BADGE OR THE LIKE

John D. Youther, Aberdeen Proving Grounds,
Md.

Application December 2, 1942, Serial No. 108,939

Term of patent 14 years

To all whom it may concern:

Be it known that I, John D. Youther, a citizen of the United States, residing at Aberdeen Proving Grounds, in the county of Harford and State of Maryland, have invented a new, original, and ornamental Design for a Badge or the like, of which the following is a specification, reference being had to the accompanying drawing, forming part thereof.

I claim:

The ornamental design for a badge or the like, as shown.

JOHN D. YOUTHER.
